United States Patent Office

Des. 212,585
Patented Nov. 5, 1968

212,585

BOTTLE

Walter S. Joy, 12 W. 55th St.,
New York, N.Y. 10019

Filed Sept. 1, 1967, Ser. No. 8,462

Term of patent 14 years

(Cl. D9—37)

FIG. 1

FIG. 2

FIG. 3

FIG. 4

FIG. 5

FIG. 6

FIG. 1 is a side elevational view of a bottle showing my new design;

FIG. 2 is a side elevational view showing the side opposite that seen in FIG. 1;

FIG. 3 is an elevational view looking from the left of FIG. 1;

FIG. 4 is an elevational view looking from the right of FIG. 1;

FIG. 5 is a bottom plan view; and

FIG. 6 is a top plan view thereof.

I claim:

The ornamental design for a bottle, as shown.
